FORM WALL SUSTAINING MEANS

Samuel S. Colt, West Orange, N. J.

Application September 9, 1939, Serial No. 294,075

4 Claims. (Cl. 254—104)

This invention relates to improvements in devices for securing and sustaining the walls of concrete casting forms in assembled relation.

This invention has for an object to provide an improved form wall sustaining device of the wedge type adapted to cooperate with form wall tie-rods so as to securely anchor the walls against displacement or yielding shift under the weight of the concrete mix when the latter is poured into the form interior.

The invention has for another object to provide a form wall locking and sustaining device comprising a wedge element and a cooperating tie rod engaging abutment member which, although relatively movable, are tied together in such manner as to provide a unit whereby the parts cannot become accidentally separated when carried about from place to place.

Another object of the invention is to provide for cooperation with the wedge element of the device a novel and improved form of abutment member so designed that it impinges the wedge element in such manner as to prevent distortion or like injury to the keeper flanges of said wedge element, and so that the stresses and strains, to which the device is subjected in use, are only transmitted to and through the vertical webs of the wedge element; and said abutment member being further reenforced to sustain the strains and stresses to which it is subjected, and, incidentally, so as to cooperate with the wedge element of a second unit, in cases where a double wedge locking arrangement is desired to be used.

Another object of the invention is to provide a novel form and construction of abutment member of the type equipped with opposed set screws for gripping a tie-rod to which said member is to be anchored in use.

Other objects of this invention, not at this time more particularly enumerated, will be understood from the following detailed description of the same.

Illustrative embodiments of this invention are shown in the accompanying drawing, in which: Fig. 1 is a fragmentary sectional view of a form wall structure, showing operative application thereto of the novel locking and sustaining means of this invention, and also showing an optional tandem arrangement of two of the latter as is sometimes desired.

Fig. 2 is an enlarged longitudinal section, showing an abutment member in elevation, said view being taken on line 2—2 in Fig. 1; Fig. 3 is a view similar to that of Fig. 2, but showing an abutment member in horizontal section; and Fig. 4

is a transverse section, taken on line 4—4 in Fig. 2.

Fig. 5 is a view similar to that of Fig. 2, but showing a modified form of abutment member.

Similar characters of reference are employed in the above described views, to indicate corresponding parts.

Illustrative of the use of the novel form wall sustaining means of this invention, the same is shown applied to a common type of form wall structure comprising, a wall member 10, which is usually spaced apart from a similar opposed wall member, these wall members being tied together by tie-rods 11 extending therebetween. Ordinarily battens 12 are employed to trace the outer side of the wall member 10, over which are usually arranged transversely extending walers 13; the latter ordinarily being associated in pairs, between the members of which an exterior end portion of a tie-rod 11 extends.

The novel form locking and sustaining device includes a wedge member comprising a base 14 having a longitudinally disposed slot 15 through which the tie-rod 11 may project. Projecting outwardly from said base 14, respectively along opposite sides of said slot 15 and perpendicular to the plane of said base 14 are wedge webs 16, the outer margins of which are downwardly and inwardly inclined to converge toward the base 14. Formed in connection with said outer margins of said wedge webs 16 are face flanges 17 disposed transverse to the plane of said wedge webs 16 so as to overhang the latter, so that freely projecting marginal portions thereof provide keeper lips. Said flanges 17 project freely beyond the lower ends of said wedge webs 16 to provide inwardly bent retainer ears 18 for purposes presently to be explained.

Cooperative with the wedge member thus provided is an abutment member having means to couple the same to and upon the outwardly projected end portion of the tie-rod 11 in fixed or in anchored relation thereto. This abutment member comprises a longitudinal main body member 19 having an axial bore 20 through which said tie-rod 11 may be extended. The inner end portion of said main body 19 is suitably cut away or reduced along opposite sides thereof and inwardly of its rear extremity so as to form oppositely and laterally projecting keeper lugs 21. In assembling the abutment member in attached operative relation to the wedge member, the former is passed upwardly between the wedge webs 16 of the latter so that the keeper lugs 21 will engage behind the keeper lips formed by the 55

interiorly projecting portions of the face flanges 17 of said wedge member, whereby the wedge member is free to move longitudinally across the end of the abutment member while, nevertheless, 5 the latter is retained against bodily separation from such operative assembled relation to the wedge member. After the abutment member has been thus operatively assembled with and related to said wedge member, the retainer ears 18 10 are bent inwardly so as to prevent the thus assembled abutment member from being slid off and away and thus detached from the wedge member, and consequently the keeper lugs 21 are retained against disassembly from operative relation to the keeper lips formed by the face flanges 17 of the wedge member.

Integrally formed in connection with the main body 19 of said abutment member are laterally and oppositely projecting bosses 22 having axial internally screw-threaded bores 23 which intersect the bore 20 of said main body 19. Threaded respectively into said bores 23 are opposed set-screws 24 which when tightened home serve to grip the tie-rod 11 extending through the bore 20 of said main body 19, and thus firmly affix or anchor the abutment member to said tie-rod. Integrally formed in connection with the rearward sides of said bosses 22 are impingement lugs or ears 25, the same being spaced outwardly from the adjacent portions of said main body by intervening indented notches 26. Said impingement lugs or ears are provided with curvilinear peripheral thrust ribs 27, which are relatively spaced apart for a distance equal to the distance apart 30 of the spaced wedge webs 16 to which they are consequently aligned. To reenforce and brace the bosses 22 against stresses and strains transmitted thereto through the thrust ribs 27, when the latter are operatively engaged by the thrust 35 40 of the driven home wedge member, bracing webs 28 are formed to extend between the outer sides of said bosses and outer end portion of the main body 19. Preferably these bracing webs extend at their outer ends in the plane of the end surface 45 of the outer extremity of said main body 19, thus providing an abutment surface to engage the base of a similar sustaining means when two such means are used in tandem, as shown in Fig. 1.

50 In the use of the sustaining means, the wedge member thereof being raised to initial position subject to downward driving movement, the same with its associated abutment member is threaded over the projecting end portion of a tie-rod 11 until the base flange 14 of the wedge member bridges and abuts the waler 13, whereupon the abutment member is affixed or anchored to the tie-rod 11 by tightening home the opposed set-screws 24, so as to strongly grip the tie-rod therebetween. When the parts are thus arranged, the thrust ribs 27 will impinge upon the face flanges 17 at points directly over and in alignment with the wedge webs 16. When the wedge member is driven down between the abutment member and the waler 13, it will thrust against the abutment member so as to draw the tie-rod 11 tight, while at the same time it will thrust against the form wall structure so as to press the same to position as determined by internal stretchers or spacers (not shown), thus firmly locking the form wall structure in place, while likewise holding the same strongly against outward displacement under the weight and pressure of the concrete, when the latter is poured into the form interior.

It will be understood that owing to the fact that thrust ribs 27 are maintained in position to bear only upon those parts of the wedge face flanges 17 which are directly over and in line with the wedge webs 16, no pressure is 5 exerted upon the freely overhanging or keeper lip portions of said flanges, and consequently risk of distortion or other mutilation thereof likely to impede or interfere with desired operative movement and manipulation of the wedge member is avoided.

If desired, as is sometimes the case, two sustaining means may be employed in tandem relation. In such case, the inner unit is left free for movement relative to the tie-rod, while the abutment member of the outer unit is anchored to the tie-rod and thereafter its associated wedge member is driven home. After the first unit has been tightened home, the wedge member of the second or inner unit is driven home to finally 20 force the form wall into desired position, whereafter the abutment member of said second or inner unit is anchored to the tie-rod by tightening home its set screws. It will be obvious that the reenforcing or bracing webs 28, by reason 25 of their position and square outer portions, form, with the outer end of the abutment member, a satisfactory bearing surface to engage the base flange of the wedge member of the outer unit so as to operatively bear and transmit the thrust 30 thereof.

In Fig. 5 I have shown a somewhat modified construction of abutment member which possesses the general features above described, including the novel form and disposition of the thrust ribs 35 27. In such modified arrangement, however, instead of forming the inner end of the main body 19 to provide keeper lugs 21 disposed to engage the interior keeper lip extensions of the wedge face flange 17, rearwardly extending arms 29 are 40 provided outwardly of the thrust ribs 27, and said arms 29 terminate in keeper lugs 21' adapted to engage the exterior keeper lip extensions of the wedge face flange 17. In this arrangement, the inner or rearward end portion of the main 45 body 19 is omitted, and said main body is concavely depressed, as at 30, to provide clearance between the projecting thrust ribs 27.

Having now described my present invention, I claim:

1. A form wall sustaining means comprising, in combination, a wedge member and a cooperating abutment member, said members each having openings for the passage of a tie-rod therethrough, said wedge member having spaced wedge webs terminating at their outer edges in transverse overhanging face flanges free margins of which provide keeper lips, said abutment member having keeper lugs cooperative with said keeper lips to hold said members against separation 60 without interfering with operative movement of said wedge member relative to said abutment member, said abutment member having means to affix the same in anchored relation to and upon a tie-rod, and said abutment member having rearwardly projected thrust ribs laterally offset therefrom in spaced relation corresponding to the spacing of said webs so as to impinge on said wedge face flanges only at points directly aligned with said wedge webs.

2. A form wall sustaining means as defined in claim 1, wherein the means for affixing said abutment member in anchored relation to a tie-rod comprises opposed set screws threaded through the sides of said abutment member.

3. A form wall sustaining means comprising, in combination, a wedge member and a cooperating abutment member, said wedge member having a longitudinally slotted base for the projection of a tie-rod therethrough, said wedge member having spaced wedge webs projecting from said base adjacently along the sides of its slot, said wedge webs terminating at their outer edges in transverse overhanging face flanges free margins of which provide keeper lips, said abutment member comprising an axially bored main body engageable over a tie-rod and provided at its inner end with laterally projecting keeper lugs cooperative with said keeper lips to hold said members against separation without interfering with operative movements of said wedge member relative to said abutment member, said main body having oppositely and laterally projecting internally threaded bosses intermediate its ends, thrust ribs rearwardly projecting from said bosses and spaced from the sides of said main body by indented intermediate notches, said thrust ribs being disposed in spaced apart relation corresponding to the spacing of said wedge webs so as to impinge on said wedge face flanges only at points directly aligned with said wedge webs, and opposed set screws threaded through said bosses and operative to grip a tie-rod therebetween so as to anchor said abutment member 10 thereto. 5
4. A form wall sustaining means as defined in claim 3 including bracing webs extending between the bosses of said abutment member and the outer portion of its main body, and said bracing ribs having end margins located in the plane of the outer end face of said main body for the purposes described. 15
